UNITED STATES PATENT OFFICE.

DAVID M. LEWIS, OF CHICAGO, ILLINOIS, ASSIGNOR TO LEWIS DRAFT APPLIANCE COMPANY, A CORPORATION OF ILLINOIS.

LOCOMOTIVE DRAFT APPLIANCE.

Application filed August 18, 1921. Serial No. 493,312.

To all whom it may concern:

Be it known that I, DAVID M. LEWIS, a citizen of the United States, residing at Chicago, in the county of Cook and State of Illinois, have invented certain new and useful Improvements in Locomotive Draft Appliances, of which the following is a specification.

This invention relates to locomotive draft appliances and it has for one of its primary objects the provision of improved means whereby the intermittent exhaust from the cylinders may be changed into a substantially continuous draft blast.

Another object of the invention is to provide a draft appliance of this character which affords minimum obstruction to the smoke box and in which access may be had to the interior of the smoke box.

The invention further relates to features of construction and combination of parts to be more fully hereinafter set forth.

The foregoing, together with such other objects as may hereinafter appear, I obtain by means of a construction which I have illustrated in preferred form in the accompanying drawings wherein:

Fig. 1 is a longitudinal section through a locomotive smoke box embodying my improvements; and Fig. 2 is a transverse section through the smoke box of Fig. 1 on the lines 2—2.

Referring now to the drawings, the smoke box, which is cylindrical, is indicated at 7; 8 is the flue sheet having the usual flues 9 and superheater flues 10; 11 are the superheater units and 12 the steam pipes. The upper portions of the saddle are shown at 13 and a portion of the exhaust passages therein at 14.

The reference number 15 denotes a stack which is elongated in cross section, with its major axis extending longitudinally of the smoke box, such stack being provided with a similarly shaped petticoat 16, the ends and sides of which, however, flare at the bottom. Bolted to the base 14' is a nozzle stand 17, such stand being divided into two longitudinal chambers or passages 18 and 19 by means of the wall 20. The top of the nozzle stand 17 is in the form of a table 21, constituting a base for a nozzle housing 22. This nozzle housing is elongated in cross section with its major axis longitudinal of the smoke box in a manner corresponding to

the stack, and mounted within the housing are two vanes 23, mounted on shafts 24, geared together in the manner indicated in Fig. 2, one of said shafts being provided with an arm 25 connected by the link 26 with arm 27 keyed to the shaft 28. The shaft 28 extends out through the side of the smoke box shell and is provided with an arm 29 connected with a dash pot piston rod 30, which is weighted as at 31. The action of the weight tends to hold the vanes closed. The vanes when open create a nozzle opening which is elongated longitudinally of the box. Steam flows to the nozzle from the passage 19, the upper wall of which has an opening 19^a for this purpose.

The forward end of the chamber 18 communicates with the inlet end 32 of an expansion or volume chamber 33 which is of annular shape, the outer wall being formed by the shell 7 of the smoke box, the inner wall by the member 34 and the front and rear walls by the members 35 and 36, respectively. The outlet end of the volume chamber 33 communicates with the chamber 19. The central opening through the volume chamber permits of access to the flues and flue sheet and also to the nozzle and nozzle stand and it is covered over by the removable plate 37.

Exhaust steam from the cylinders is lead to the base cavity 14 in the usual manner and from such cavity it flows to the chamber 18, then to the inlet 32 of the volume chamber, flowing around the volume chamber 33 through the outlet 32^a thereof into the chamber 19, and thence to the nozzle. When the pressure in the volume chamber builds up to the value at which it will overcome the effect of the weights 31, the vanes 23 will open and a continuous flow or blast of exhaust steam will take place through the nozzle opening thus created as long as the locomotive is using steam. The pulsations of the exhaust blast from the cylinders are ironed out by the expansion taking place in the volume chamber, which is of such size (preferably at least several times the capacity of the cylinders) as to permit the exhaust steam to expand considerably, thereby insuring continuity of the blast during the interval between cylinder exhaust. The exhaust steam is thus discharged from the nozzle in the form of a thin, long column of relatively low pressure and low velocity.

Should the pressure in the expansion chamber tend to increase, the vanes will open more widely, thus creating a larger nozzle opening; and the pressure will automatically be lowered to the predetermined selected value, necessary to secure adequate draft for all operating speeds for the particular type of locomotive and class of service. If the pressure should tend to fall, the action of the weights will be to close the vanes, making the nozzle opening smaller, which will have a tendency to again build up the pressure to the desired value necessary to produce adequate draft. The vanes, therefore, constitute an automatic governor mechanism responsive to exhaust pressure conditions and operating to maintain the back pressure within the maximum necessary to produce adequate draft for the particular locomotive and class of service.

The exhaust draft column presents a maximum entrainment area and thus creates an effective draft. Notwithstanding the disposition of the nozzle lengthwise of the smoke box, the continuous draft blast operates to draw effectively on all of the flues—the side flues as well as the center flues—because the greatest entrainment areas are at the sides of the column and therefore a curvilinear sweep of the products of combustion from the side flues takes place and thus the side flues are worked substantially equally with the center flues, securing advantages and obviating difficulties well understood in this art. At the same time the disposition of parts is such as to afford a minimum obstruction to the smoke box, permitting ready access to flues and flue sheets and superheater units as well as to the nozzle proper and its associated parts.

What I claim is:

1. In a locomotive draft appliance, the combination of an elongated nozzle having its major axis longitudinal of the smoke box, a similarly shaped and disposed stack, and a volume chamber.
2. In a locomotive draft appliance, the combination of an elongated nozzle having its major axis longitudinal of the smoke

box, a similarly shaped and disposed stack, and a volume chamber in series with the nozzle.

3. In a locomotive draft appliance, the combination of an elongated nozzle having its major axis longitudinal of the smoke box, a similarly shaped and disposed stack, and the volume chamber in series with the nozzle, said nozzle having automatic means for creating the nozzle opening responsive to pressure conditions obtaining on the exhaust side of the cylinders.

4. In a locomotive draft appliance, the combination with the saddle casting having an exhaust passage, of a nozzle, a volume chamber, having an inlet and an outlet, and a nozzle stand having two passages, one connecting said exhaust passage and said inlet and the other connecting said outlet and the nozzle, the nozzle being elongated with its major axis longitudinal of the smoke box.

5. In a locomotive draft appliance, the combination of a smoke box, a flue sheet and its flues, an elongated nozzle the major axis of which is longitudinal of the smoke box, and an annular volume chamber in the front of the smoke box connected with the nozzle affording access to the interior through the central opening thereof.

6. In a locomotive draft appliance, the combination of an elongated nozzle having its major axis longitudinal of the smoke box, and a volume chamber in series with the nozzle.

7. In a locomotive draft appliance, the combination of a smoke box, a flue sheet with its flues, an elongated nozzle the major axis of which is longitudinal of the smoke box, and an annular volume chamber in series with said nozzle, access to the nozzle and flues being had through the central opening of the annular volume chamber.

8. In a locomotive draft appliance, the combination of an elongated nozzle having its major axis longitudinal of the smoke box and a similarly shaped and disposed stack.

In testimony whereof, I have hereunto signed my name.

DAVID M. LEWIS.
